UNITED STATES PATENT OFFICE.

ARCHIE W. FARRELL AND HARRY KELLER, OF CHICAGO, ILLINOIS, ASSIGNORS TO
PUGH STORES COMPANY, A CORPORATION OF MAINE.

VALVE MECHANISM FOR INTERNAL-COMBUSTION MOTORS.

1,246,732.

Specification of Letters Patent.

Patented Nov. 13, 1917.

Application filed August 14, 1916. Serial No. 114,723.

To all whom it may concern:

Be it known that we, ARCHIE W. FARRELL and HARRY KELLER, citizens of the United States, and residents of Chicago, in the 5 county of Cook and State of Illinois, have invented certain new and useful Improvements in Valve Mechanism for Internal-Combustion Motors, of which the following is a specification.

10 This invention relates to valve mechanism for internal combustion motors and more particularly to a valve of this class which is located within the cylinder head.

The principal objects of the invention are 15 to locate a combined intake and exhaust valve for four cycle motors in the cylinder head and over the piston in such position that the gases can be quickly drawn in and exhausted, to operate said valve by cam 20 mechanism and to so construct and arrange the parts that they can be easily exposed for inspection or repair.

The above and other objects are accomplished as hereinafter described, and as particularly pointed out in the appended claims, reference being had to the accompanying drawings in which an embodiment of the 25 invention is shown.

In the drawings:

30 Figure 1 is a fragmentary top plan view of the cylinder head of an internal combustion motor with a cam shaft and block cam mounted thereon.

35 Fig. 2 is a fragmentary section taken on line 4—4 of Fig. 3, with the exhaust ports closed and the inlet ports open.

Fig. 3 is a vertical fragmentary section through the cylinder head on line 3—3 of Fig. 1.

40 Fig. 4 is a fragmentary section taken on line 4—4 of Fig. 3, with both the inlet and exhaust ports closed.

In referring to the embodiment of the invention shown in the accompanying drawings in detail, like numerals designate corresponding parts.

The fragment of a cylinder 1, shown is of the conventional four cycle type, and is provided with the usual cylinder head 2, in 50 which a spark plug 3, is mounted.

A box 4, is arranged on the cylinder head at one side of the spark plug, in which box a cam shaft 5 is journaled.

Upon the cam shaft 5 is mounted a cir-

cular block 6, which is provided with two 55 cam grooves 7 and 8 (see Fig. 1).

The cam shaft may be driven in any of the usual ways from the motor.

A hollow member or tube 9 depends vertically from the upper part of the cylinder head within the same and forms a bearing in which two rock shafts 10 and 11 are journaled, the shaft 10 being tubular and surrounding the other shaft 11 which is preferably solid.

60 Crank arms 12 and 13 extend laterally from the upper portions of the said shafts and carry rollers 14 and 15 at their outer portions, which rollers extend within and travel in the cam grooves 7 and 8.

65 A circular valve chamber 16 is formed within the walls of the cylinder head which chamber is concentric with and surrounds the lower portion of the two shafts 10 and 11.

70 Within the valve chamber, is arranged a combined inlet and exhaust valve which is composed of two opposed separate segmental members, 17 and 18, mounted on the outer extremities of two oppositely projecting arms 19 and 20.

75 The inner ends of the arms are attached to the lower portions of the two shafts 10 and 11, so that the alternate movement of the shafts by the block cam will correspondingly rock the segmental members.

80 Inlet and exhaust ports 21 and 22 are formed in the side wall of the circular valve chamber and corresponding ports 23 and 24, are formed in the segmental valve members.

85 An outwardly extending lip or flange 25 is formed on each segmental member near the upper edge thereof which fits and slides in a groove 26 in the wall of the valve chamber, as shown in Fig. 3 and thus supports 90 the valve members in position in said chamber.

95 The valve chamber, it will be noted, is practically in the form of a vertical tube having open upper and lower ends and slots 100 or ports in its sides, and the valve members are movably mounted around an axis, the center line of which is the center line of the cylinder.

105 To maintain the segmental valve members in position, expansion rings 27 are fitted in place as shown in Fig. 3.

Upon opposite sides of the walls of the

valve chamber are bolted or otherwise detachably secured, tubular connections 28 and 29, which are attached to pipes leading respectively to the muffler or exhaust and the source of gas supply.

6 The inner ends of the connections are enlarged and with the wall of the valve chamber form side inlet and exhaust chambers 30 and 31 which are located upon opposite sides of the valve chamber.

10 The cam grooves are so formed and arranged that the segmental valve members will open and close in their proper order.

15 The parts of the improved valve are few in number, of substantial strength and can be easily exposed for repair or replacement by removing the connections 28 and 29.

20 To prevent the segmental valve members wearing a shoulder on the walls of the valve chamber, said chamber is recessed or cut away at 32 as shown in Figs. 2 and 4.

25 In practice it is perhaps advisable to place a cover (not shown) over the cam shaft box as a protection against dirt or dust.

30 The improved valve mechanism can be quickly dismounted by removing the cylinder head 2 and the tubular connections 28 and 29.

35 This exposes the valve both on the top and sides so that the parts thereof can be easily withdrawn.

40 The segmental members are preferably attached to the outer extremities of the arms 19 and 20 by longitudinally splitting and spreading the outer portions of said arms as shown at 32^a in Figs. 2 and 4, thereby forming spring holding parts which are fitted within recesses formed in enlarged portions 33 on the inner surface of the segmental members.

45 The spreading action of these split parts causes them to frictionally engage and grip the side walls of the recesses and thus secure the arms to the segmental members.

50 The two shafts are removed when the cylinder head is lifted off and carry with them the arms 19 and 20, thus dismantling the valve so that the segmental members can be easily removed.

55 The advantage of making one shaft hollow and the other solid and fitting the solid shaft through the hollow shaft is that they are both supported in a single bearing, are compactly arranged and are removed from and attached to the cylinder with the cylinder head.

60 As the segmental members are adjustably fitted on the ends of the connecting arms they are forced tighter against the wall of the valve chamber as the compression within the cylinder increases, thus producing a practically nonleaking valve.

65 From Figs. 2 and 4 it will be noted that the segmental members overlap the walls of

the valve chamber and thus overtravel their seat, which prevents wearing a shoulder on the same.

In Fig. 3 a fragment of a piston 34 is shown to illustrate the position of the valve mechanism relative to the piston.

Having thus fully described our invention, what we claim as new and desire to secure by Letters Patent is—

1. In a valve mechanism for internal combustion motors, a cylinder, a head therefor, a central valve chamber within said cylinder head having inlet and exhaust ports, a segmental valve slidably mounted in the valve chamber and also having ports, said valve consisting of independently movable segmental members having their ends spaced apart and adapted to move in the same plane, two vertical shafts journaled in the cylinder, one being tubular and surrounding the other, arms extending from the shafts and connecting to the members of the segmental valve and cam mechanism on said head for rocking the shafts.

2. In a valve mechanism for internal combustion motors, a cylinder, a central valve chamber within said cylinder having inlet and exhaust ports, a segmental valve slidably mounted in the valve chamber and also having ports, said valve consisting of independently movable segmental members adapted to move in the same plane and having their ends spaced apart, two vertical shafts journaled in the cylinder, one being tubular and surrounding the other, arms extending from the shafts and connecting to the members of the segmental valve, a cam shaft rotatably mounted over the cylinder, a cam on said shaft and crank arms extending from the two vertical shafts and engaging the cam.

3. In a valve mechanism for internal combustion motors, a cylinder, a head therefor and a segmental valve mechanism centrally located in the explosion chamber of said cylinder head and consisting of a stationary circular wall or tube provided with side ports and an inner supporting groove and movable segmental valve parts within said tube having lips or flanges fitting in the supporting groove, said segmental valve parts being adapted to move in the same plane and having their ends spaced apart.

4. In a valve mechanism for internal combustion motors, a cylinder, a removable cylinder head, two removable tubular connections attached to the side of the cylinder and extending respectively to a source of gas supply and the exhaust, a tubular valve chamber within the cylinder having inlet and exhaust ports, a valve mechanism composed of two segmental members arranged within the tubular valve chamber, one constituting an inlet valve part and the other an exhaust valve part, said segmental mem-

bers having ports, cam mechanism carried by the cylinder head, two shafts controlled by the cam mechanism, one of said shafts being hollow and surrounding the other, 5 arms extending from said shafts, and spring means for adjustably connecting said arms to the segmental members.

5. In a valve mechanism for internal combustion motors, a cylinder, a removable cylinder head, two removable tubular connections attached to the side of the cylinder and extending respectively to a source of gas supply and the exhaust, a tubular valve chamber within the cylinder having inlet 10 and exhaust ports, a valve mechanism composed of two segmental members arranged within the tubular valve chamber, one constituting an inlet valve part and the other an exhaust valve part, said segmental members having ports, cam mechanism carried by the cylinder head, two shafts controlled by the cam mechanism, one of said shafts being hollow and surrounding the other, arms 15 extending from said shafts, the outer extremities of said arms being split to form spring parts and enlarged portions on the segmental members provided with recesses in which the split ends of said arms are fitted.

20 6. In a valve mechanism for internal combustion motors, a cylinder, a removable cylinder head, two removable tubular connections attached to the side of the cylinder and extending respectively to a source of gas supply and the exhaust, a tubular valve 25 chamber within the cylinder having inlet and exhaust ports, a valve mechanism composed of two segmental members arranged within the tubular valve chamber, one constituting an inlet valve part and the other an exhaust valve part, said segmental members having ports, cam mechanism carried by the cylinder head, two shafts controlled by the cam mechanism, one of said shafts being hollow and surrounding the other, and arms extending from the shafts and detachably connected to the segmental members.

chamber within the cylinder having inlet and exhaust ports, a valve mechanism composed of two segmental members arranged within the tubular valve chamber, one constituting an inlet valve part and the other 40 an exhaust valve part, said segmental members having ports, cam mechanism carried by the cylinder head, two shafts controlled by the cam mechanism, one of said shafts being hollow and surrounding the other, 45 and means detachably connecting the shafts to the segmental members.

7. In a valve mechanism for internal combustion motors, a cylinder, a removable cylinder head, two removable tubular connections attached to the side of the cylinder and extending respectively to a source of gas supply and the exhaust, a tubular valve chamber within the cylinder having inlet 50 and exhaust ports, a valve mechanism composed of two segmental members arranged within the tubular valve chamber, one constituting an inlet valve part and the other an exhaust valve part, said segmental members having ports, cam mechanism carried by the cylinder head, two shafts controlled by the cam mechanism, one of said shafts being hollow and surrounding the other, and arms extending from the shafts and detachably connected to the segmental members.
